UNITED STATES PATENT OFFICE.

CHARLES T. WITTSTEIN AND FRANCIS H. WITTSTEIN, OF NEWARK, NEW JERSEY.

DESIGN FOR A MONOGRAM MEDALLION RING.

Application filed May 29, 1924. Serial No. 9,749. Term of patent 14 years.

To all whom it may concern:

Be it known that we, CHARLES T. WITTSTEIN and FRANCIS H. WITTSTEIN, citizens of the United States, and residents of Newark, in the county of Essex and State of New Jersey, have invented a new, original, and ornamental Design for Monogram Medallion Rings, of which the following is a specification, reference being had to the accompanying drawing, forming a part thereof.

The figure is a perspective view of a monogram medallion ring, showing our new design.

We claim:

The ornamental design for a monogram medallion ring, as shown.

CHARLES T. WITTSTEIN.
FRANCIS H. WITTSTEIN.
